Walter G. Strong Inventor
Samuel A. Rounds
For D. L. & Co. Atto

UNITED STATES PATENT OFFICE.

SAMUEL H. ROUNDS AND WALTER L. STRONG, OF SAN FRANCISCO, CAL.

MACHINE FOR CONCENTRATING THE DUST FROW ORES, MILLS, &c.

Specification forming part of Letters Patent No. 43,646, dated July 26, 1864.

To all whom it may concern:

Be it known that we, SAMUEL H. ROUNDS and WALTER L. STRONG, of the city and county of San Francisco and State of California, have invented a new and Improved Ore-Dust-Concentrating Machine, called "Strong & Rounds's Ore-Dust-Concentrating Machine," for the purpose of concentrating the dust arising from the pulverizing or grinding of metallic ores; and we do hereby declare that the following is a full, clear, and exact description of the same, together with its construction and operation, reference being had to the annexed drawings, making a part of this specification.

The nature of our invention consists in providing a machine for collecting and concentrating the dust arising from the crushing of metallic ores and preparing the same for amalgamation; also, to prevent the danger arising from inhaling the dust by those engaged in and around quartz-mills, which inhalation is attended by very serious consequences, especially when the ore is impregnated with arsenic or antimony.

To enable others skilled in the art to make and use our invention, we will proceed to describe its construction and operation.

We construct a room or chamber of wood of any dimensions required, which is placed in the stamp-room or outside of the building, as the case may be. At the extreme left corner of this chamber is placed a condensing apparatus. The ore dust is drawn from the battery by means of a suction-fan, and is forced into the chamber, where, by a current of air, it is carried into a steam-chest at the top of the condenser, when it falls or is washed down into the receptacle at the bottom of the condenser and is prepared for amalgamation.

In the drawings, Figure 1, A represents the concentrating-room, together with the front elevation of the condenser. B is the draft-tube through which the dust is forced by means of the suction-fan into the chamber. C is the top of the condenser left open. D is a funnel-shaped tube, into which the ore-dust is

drawn. E is a steam-pipe which supplies the steam-chest F. G is an opening leading from the steam-chest into the condenser. H H are water-pipes. The bottom one is a supply-pipe, the top one a waste-pipe. J is the pipe which allows the water and concentrated ore to pass off from the bottom of the condenser. O O are legs.

Fig. 2 is a top view of the condenser with a perforated covering. D is the funnel-shaped tube leading to the steam-chest F. E is a steam-pipe. G G G G is an opening from the steam-chest into the condenser. H H are supply and waste pipes. The bottom one supplies the cylinder-jackets I I I I. The top one is the waste-pipe. L L L L are couplings. K K K K are hollow cylinders. M M M are connecting-pipes.

In Fig. 3, H H are water-pipes. I I I I are cylinder-jackets. K K K K are inside cylinders. L L L L are couplings; N N, bottom of the condenser; O O, legs; J, outlet.

Fig. 4 is a top view of the condensing cylinders. (Shown in detail) N N, are pipes through which the ore and water is carried to the bottom of the condenser.

Fig. 5 is a perspective view of the condensing cylinder. H H are exhaust and supply-pipes. I I I I are outside cylinders containing water; J, outlet. K K are cylinders; M M, couplings; N N, bottom of condensing cylinders; O O, legs.

We do not claim a chamber or room for concentrating ore-dust; neither do we claim the forcing of the dust into the chamber by means of a suction-fan; but

We claim—

A machine for concentrating ore-dust with a sufficient condensing surface, for the purpose and in the manner substantially as described and set forth.

S. H. ROUNDS.
WALTER L. STRONG.
